UNITED STATES PATENT OFFICE

ABRAHAM LEVY, OF BROOKLYN, NEW YORK

DESIGN FOR A BANJO-CLOCK CASE OR SIMILAR ARTICLE

Application filed November 17, 1930. Serial No. 37,688. Term of patent 7 years.

To all whom it may concern:

Be it known that I, ABRAHAM LEVY, a citizen of the United States, residing at Brooklyn, N. Y., in the county of Kings and State of New York, have invented a new, original, and ornamental Design for a Banjo-Clock Case or Similar Article, of which the following is a specification, reference being had to the accompanying drawing, forming part thereof.

The figure is a perspective view of a banjo clock case or similar article, showing my new design.

The back of the clock is flat and unornamented.

I claim:

The ornamental design for a banjo clock case or similar article, as shown and described.

ABRAHAM LEVY.
